UNITED STATES PATENT OFFICE.

WILLIAM H. DURANT, OF SOMERVILLE, MASSACHUSETTS.

DOOR-CONTROLLER.

1,331,329.

Specification of Letters Patent. Patented Feb. 17, 1920.

Application filed January 31, 1919. Serial No. 274,168.

To all whom it may concern:

Be it known that I, WILLIAM H. DURANT, a citizen of the United States, residing at Somerville, county of Middlesex, State of Massachusetts, have invented an Improvement in Door-Controllers, of which the following description, in connection with the accompanying drawing, is a specification, like characters on the drawing representing like parts.

This invention relates to a door controller or a device for controlling the opening or closing of a door.

The object of the invention is to provide a controller which shall be simple in its construction, efficient in its action, and which shall not be likely to get out of order under the severe conditions of usage to which such a device is subjected.

The object of the invention is to provide a door controller which shall check or retard the door at the end of its movement as in closing so that the door will not slam nor pinch the fingers if resting on the jamb.

The object of the invention is to provide a door controller in which a signal shall be actuated at a predetermined point in the opening or closing movement of the door.

These and other features of the invention will appear more fully from the accompanying description and drawings and will be particularly pointed out in the claims.

The drawings show preferred forms of structures embodying the invention.

In the drawings, Figure 1 is a side elevation largely in vertical cross-section of a door controller embodying the invention and designed for effecting the closing of the door; for checking the door in the latter portion of its opening movement, for retaining the door at the end of its opening movement in open position, and for checking the door in the latter portion of its closing movement;

Fig. 2 is a view in transverse section taken on the line 2-2 of Fig. 1;

Fig. 3 is a view in transverse cross section taken on the line 3-3 of Fig. 1;

Fig. 4 is a plan view of a door with a device such as shown in Fig. 1 applied thereto, the door being shown closed in full lines and open in dotted lines;

Fig. 5 is a view similar to Fig. 1 but of another form of construction embodying the invention in which a signal is provided actuated during the latter portion of the open-

ing movement of the door, in which no provision is made for opening or closing the door by the action of the controller itself, and in which the guide or socket member is 60 of circular cross section;

Fig. 6 is a side elevation of the upright portion of the construction shown in Fig. 5;

Fig. 7 is a view in transverse cross section taken on the line 7-7, Fig. 5; 65

Fig. 8 is a view in transverse cross section taken on the line 8-8, Fig. 5;

Fig. 9 is a plan view showing a door with the construction shown in Fig. 5 applied thereto, the door being shown closed, and 70 the controller being shown connected from the door to a wall extending at right angles to the door;

Fig. 10 is a view similar to Fig. 1 in which the construction is designed to return a door 75 to an intermediate position when swung in either direction therefrom;

Fig. 11 is a plan view showing a door and a device such as shown in Fig. 10 applied thereto, the door being shown in full lines 80 in its closed or intermediate position and in dotted lines in positions to which it may be opened in opposite directions;

Fig. 12 is a view in side elevation and partially in vertical cross section taken on the 85 line 12-12, Fig. 10.

This invention presents a device which may take various forms depending upon the results which it is desired to secure. It is capable of controlling the movement of the 90 door in various ways and under a variety of conditions. In its preferred form it is more particularly designed for effecting the closing movement of a swinging door.

A simple and preferred construction for 95 effecting the closing movement of the swinging door is shown in Figs. 1 to 4 inclusive of the drawing.

A door 1 of an ordinary swinging type is shown as hinged at 2 to the usual relatively 100 fixed support such as the vertical jamb 3. The door when closed aligns with the jamb 4 at the other side.

The controller comprises essentially relative sliding members 5 and 6 one of which 105 is connected to the door and the other of which is connected to the relatively fixed support such as the jamb. In the case of the usual swinging door these members are connected to the door and fixed support respectively by pivotal connections. In any case the relative sliding movement of the

two members is availed of for securing the desired, usually the closing, movement of the door.

In the preferred form of the invention the two members of which the controller is formed are a hollow socket member 6 and a plunger member 5 sliding in the socket member. In the form shown in Fig. 1 this socket member is formed of square metal tubing 10 to present the hollow square section shown in Fig. 3. At its pivotal end it is drawn down, formed or reinforced to present the hinged tongue 7 which is loosely pivoted between the lugs 8 of a bracket 9 secured to 15 the jamb 3. The pivot may be an ordinary headed pin 10 held in place by a cotter pin 11. The opposite end of this guide or socket member 6 is left open for the coöperating or plunger member 5.

20 The plunger member 5 is preferably solid and presents a shank which at one end is formed into a hinged tongue 12 pivoted to a bracket 13, similar to the bracket 9, and secured to the door 1. This plunger member at a point which is opposite the open end of the socket member when the members are at their greatest elongation in use is recessed about its periphery and into this recess is fitted suitable packing material 14. 25 Thus as the relative sliding movement of the two members takes place oil and grease are prevented from passing out of, and dirt and foreign substance are prevented from passing into the interior of the socket member.

30 The inner or telescoping end of the guide or plunger member is preferably of a cross section to correspond in general with the interior cross section of the socket member and fits loosely therein so as to avoid friction but at the same time maintains the two members in alinement. Suitable anti-friction devices are preferably provided between the two members. For this purpose the member 5 is shown as provided at the 35 bottom at a plurality of points with recesses extending transversely and having the shape of the major segment of a cylinder. Roller bearings 15 are slipped endwise into these recesses, are of a length to fit quite 40 closely against the side walls of the socket members, and project slightly below the bottom of the plunger member and thus ride upon the bottom of the socket member.

45 The coöperating action of the relatively sliding members of the device is effected through or by the agency of a follower mounted upon the one member and pressed laterally against a lateral surface of the other member. This construction is preferably secured by providing a follower casing rigidly secured to and projecting laterally from the socket member. In the form shown in Figs. 1 to 4 this follower casing 16 is made of square tubing of the same character as the socket member 6 and is brazed or

welded at 17 to the edges of a square opening in the top surface of the socket member. The follower is conveniently shown as an anti-friction roll 18 journaled in the lower end of a follower plunger 19 which is preferably of rectangular cross section to fit and slide easily in the interior of the casing 16. The follower casing may be closed by a cap 20 and held in place by threaded screws 21 passing through the side wall of the casing 16 into lugs 22 depending from the cap.

70 The follower is yieldingly pressed against the coöperating sliding or plunger member 5 by a helical spring 23 seated at the bottom in a circular recess in the follower 18 and at the top against a collar 24 threaded to a screw threaded pin 25 passing through an opening in the cap 20. This collar 24 is prevented from rotating with respect to the casing 16 and for that purpose 85 is shown as square in cross section and fitting the interior of the casing. The pin 25 is provided with a flange 26 fitting against the bottom of the cap 20 and a lock nut 27 is threaded onto the upper end of the pin. 90 Consequently, by turning the pin as by inserting a screw driver in the slot 28 the collar 24 is raised or lowered to adjust the tension of the spring 23 and when the proper tension is obtained the lock nut 27 is set up 95 and the adjustment thus maintained.

100 In order to prevent accidental separation of the plunger and socket members, especially before the device is installed the inner end of the plunger member is upturned at 29 to contact with the follower 18 thus rendering it necessary to remove the cap 20 and raise the follower when it is desired to separate the two members.

105 The control of the relative sliding movement of the members and consequently of the movement of the door is effected by the action of the follower upon the opposed lateral surface of the coöperating sliding member which in this case is the plunger member 5 and this lateral surface may be shaped to give any required result.

110 For example, when the door is of the swinging type illustrated and is being closed either automatically or manually it is frequently desirable to check this closing movement near its end so that the door will not slam or so that it will not strike and injure a person's fingers resting on the jamb. This 115 checking of the final closing movement is provided for by arranging a lateral projection 30 near the inner end of the plunger member so that as the door is nearly closed the follower 18 riding up over this projection will check the relative sliding movement of the two members, which in this case is an extending movement. It is obvious that the shape and number of the projections 30 may be varied to secure any such desired 120 result.

Again, for example, it may be desirable to retain the door at some predetermined open position, that is, either where it is partially or wide open. This result may be secured by providing one or more recesses 31 at the required point in the lateral surface of the plunger member opposed to the follower. Consequently, when either under manual or automatic action the movement 10 of the door, as in opening, is effected and as in this case by a contracting action of the sliding members, the follower 18 coming opposite the recess 31 will drop thereinto and if movement is not then checked will drop 15 into the next recess and so on. In any event, one or the other of these recesses will act to check the door and to maintain it at the required position. The tension of the spring 23, the depth of the recesses and their position 20 define the point at which the movement of the door will be stopped and the suddenness with which it will be checked.

The recesses 31 with the projections 32 may also act in co-operation with the follower 25 to perform other functions such as the operation of a signal, as is more fully illustrated hereinafter.

Again, for example, the automatic movement of the door in either direction may be effected. The movement which it is usually desired to effect is a closing movement and a construction for this purpose is also illustrated. This is secured by providing a lateral surface 33 on the plunger member of 35 the required length and inclined toward the inner end. This surface is so positioned with respect to the follower that when the follower rests at any point on the inclined surface it will wedge or press the plunger member outwardly until the lowest point of 40 the inclined surface comes opposite the follower. In the form illustrated this results in an extending sliding movement of the two members and in the automatic closing of the door. The position of this inclined surface, 45 its extent, and its angle together with the tension of the spring 23 enable any required movement of the door to be effected automatically by a controlling device. In the case of heavy door or doors which move 50 with difficulty auxiliary means may also be provided for assisting in this automatic movement, such as the closing movement of the door. Such an auxiliary means is illustrated as a helical spring 34 coiled about the exterior of the relative sliding members 5 and 6, abutting at one end against the plunger casing 16, and abutting at the other end 55 against a screw collar 35 having a threaded engagement with the shank 5 of the plunger member. Consequently, the tension of the spring 34 may be adjusted as required.

The lubrication of the device is readily effected because all the working parts are 60 closed and the inclosed space sealed up

against leakage of the lubricant by the packing 14. The interior of the follower plunger casing 16 is preferably in communication with the interior of the socket member through a lubricating passage-way 36 in the 70 follower plunger. Hence, a suitable lubricant introduced into the plunger casing works down into the interior of the socket member and thus all the working parts are lubricated.

75 Another form which a controlling device embodying the present invention may take and which shows some of the further possibilities of the invention is illustrated in Figs. 5 to 9 inclusive of the drawings.

80 In this form the relative sliding members are again shown as a hollow or socket member 37 and a plunger member 38. The members are again shown as controlling the action of a swinging door 39 pivoted at 85 40 to a jamb 41. In this case, however, the plunger member 38 is shown as pivoted to the door while the socket member 37 is shown as having its pivotal bracket 42 secured to a wall 43 extending at right angles 90 from the jamb 41, an arrangement which is frequently necessary.

95 The socket member 37 is here shown as made of cylindrical tubing and the plunger member 38 as made from a round rod. Packing 44 is fitted into a recess in the plunger member in a manner similar to that already described. Anti-friction devices are also provided between the telescoping portions of the two members and in this case 100 are shown as balls 45 resting in the longitudinal recess 46 in the plunger member and having their movements limited by pins 47 and by the end wall 48 of the recess.

105 The follower casing 49 is preferably cylindrical on the exterior and brazed or welded to the socket member so as to project laterally therefrom. The interior of the follower casing is preferably square in cross section. The follower plunger 50 has 110 a square exterior to fit therein and is provided with a follower 51 again shown as an antifriction roll. The cap 52 of the follower casing is secured in place by screws 53 passing through the walls of the casing 115 into or against lugs 54 depending from the cap. The pressure of the follower is regulated in a manner already described by the helical spring 55 seated at the bottom in a circular recess in the follower plunger 50 120 and abutting at the top the collar or nut 56 threaded to the tubular member 57 having the collar or flange 58 beneath the cap and the knurled head or thumb piece 59 above the cap. The nut 56 is square in cross section as before and is freely slideable in the casing 49 so that as the pin member 57 is turned this nut slides up or down to adjust 125 the tension of the spring.

130 The follower plunger 50 is shown pro-

vided with a rod or pin 60 extending up through the interior of the hollow member 57 and projecting above the head 59. Consequently the movement of this pin may be utilized to operate a signal or perform any similar function.

Such a signal may be of any type of nature. In order to illustrate this feature an audible signal has been selected and is shown 10 as a bell or gong 61 the mechanism of which is actuated to give a sound when the button 62 is pressed. This bell is shown as provided with a supporting rod 63 and held in place by this rod passing through a socket 15 in a lug 64 projecting from the cap 52. A set screw 65 locks the parts in position. Consequently, when the follower is raised sufficiently to press the button 62 the bell will be actuated.

20 The movement of the follower to effect the actuation of the signal or the movement of the pin 60 for whatever purpose is again secured by providing projections and recesses at the required points and of the required proportions upon the opposed lateral surface of the opposed sliding member, in this case the plunger member. A series of such projections 66 with intermediate recesses 67 are illustrated and in the present 25 case will act to ring the bell near the latter portion of the opening movement of the door.

In the construction shown in Figs. 5 to 9 inclusive the relative sliding members are not arranged to open or close the door automatically and consequently a flat surface 68 is shown along which the follower rides allowing the door to be opened or closed by hand. The projection 69 with the recesses 70 30 at each side check the door near the end of its closing movement preventing slamming or injuring of the fingers and the stop 71 prevents the accidental separation of the sliding members.

45 Still another illustration of the scope of this invention is afforded by the construction shown in Figs. 10 to 12 inclusive of the drawings. This construction is particularly designed to effect the closing movement of that type of swinging door which is adapted 50 to swing open in either direction. The relative sliding members are again shown as a socket member 72 and a plunger member 73, the socket member being made of squared 55 tubing as already described. In this case the door 74 has a reversible hinge 75 by which it may swing either into the dotted line position 76 or the dotted line position 77. The socket member 72 is pivotally secured by its bracket 78 directly to the door while the plunger member 73 is pivotally secured by its bracket 79 to the jamb. Owing to the fact that the door swings in either direction it is necessary to bend the 60 65 shank of the plunger member 73 substan-

tially at right angles to itself to enable it to reach around the jamb. The relative sliding movement of the two members is determined, however, by variation in distance between the brackets 78 and 79 so that the 70 operation is not effected by this bend in the shank.

In this construction the closing movement of the door is the one which is effected. When the door is swung into one position 75 the closing movement is effected by a relative contracting sliding movement of the two members and when it is swung into the other position by a relative extending movement of the two members. 80

The follower plunger casing 80 and the follower 81, the helical spring 82 and the means for adjusting the tension of the spring may be and are shown as of a similar construction to that illustrated and described in connection with Figs. 1 to 4. So also the anti-friction devices between the telescoping plunger and socket members are again shown as roller bearings 83.

The lateral surface of the sliding member, 90 in this case the plunger member, opposed to the follower 81 consists of two inclined sections 84 and 85 inclined toward each other and toward the bottom of the plunger and terminating in stop surfaces 86 and 87 respectively. These surfaces are so arranged as to length, inclination and position as to give the proper control to the movement of the door. With the parts shown in the position illustrated in Fig. 10 the door will be 100 closed and held in closed position by the follower resting at the point where the two inclined surfaces 84 and 85 come together. Consequently as the door swings in either direction the follower will ride up one or 105 the other of the inclined surfaces and immediately the door is released the follower will act through the relative sliding movement of the two members to return the doors to closed position. Stop surfaces 86 and 87 110 may also be arranged and utilized to limit the extreme open position of the door in either direction.

From these illustrations of several forms which the invention may take it will be seen 115 that the invention is capable of a wide variety of constructions and of varied combinations of the various features disclosed to effect a wide variety of results, and it is to be understood that the specific embodiments 120 illustrated are simply for the purpose of disclosing some of the forms which the invention may take and are not to be considered as restrictive of the invention nor is the invention to be limited other than as 125 defined by the claims.

Having fully described my invention what I claim as new and desire to secure by Letters Patent is:

1. A door controller comprising relatively 130

sliding members connected respectively to the door and a relatively fixed support, and means acting transversely of said members for effecting the relative sliding movement of said members to effect the movement of the door.

2. A door controller comprising relatively sliding members connected respectively to the door and a relatively fixed support one of said members presenting a lateral surface inclined toward its axis, a follower mounted on the other member, and means for pressing said follower toward the opposing member whereby when the follower is opposite said inclined surface a relative sliding movement of said members will be effected to effect the movement of the door.

3. A door controller comprising relatively sliding plunger and socket members connected respectively to the door and a relatively fixed support, the said plunger member presenting a lateral surface inclined toward its axis, a follower mounted on the socket member, and means for pressing said follower toward the plunger member whereby when the follower is opposite said inclined surface a relative sliding movement of said members may be effected to effect the movement of the door.

4. A door controller comprising relatively sliding members connected respectively to the door and a relatively fixed support, and means acting transversely of said members for retarding the relative movement of said members during the latter portion of the movement of the door.

5. A door controller comprising telescoping plunger and guide members pivotally connected respectively to a swinging door and a relatively fixed support, and means acting transversely of said members for retarding the relative movement of said members during the latter portion of the swinging movement of the door.

6. A door controller comprising telescoping plunger and guide members pivotally connected respectively to a swinging door and a relatively fixed support, and means for retarding the relative extending movement of said members during the latter portion of the closing movement of the door.

7. A door controller comprising relatively sliding members connected respectively to the door and a relatively fixed support, a plurality of lateral projections on one of said members, a follower mounted on the other member, and means for yieldingly pressing said follower toward said opposing member whereby the movement of said members is retarded at a predetermined point in the movement of the door.

8. A door controller comprising relatively sliding members connected respectively to the door and a relatively fixed support, a

signal, and means for actuating said signal at a predetermined point in the movement of the door.

9. A door controller comprising relatively sliding members connected respectively to the door and a relatively fixed support, a signal, and means actuating said signal from and during the latter portion of the contracting movement of said members.

10. A door controller comprising relatively sliding members connected respectively to the door and a relatively fixed support, a signal, and means for simultaneously actuating said signal and retarding the contracting movement of said members during the latter portion of the opening movement of the door.

11. A door controller comprising relatively sliding members connected respectively to the door and a relatively fixed support, a signal, a follower mounted on one of said members, and means for yieldingly pressing said follower toward the other of said members, a lateral projection on the opposed member, whereby as the door is moved to bring the said projection opposite the said follower the signal will be actuated.

12. A door controller comprising relatively sliding members connected respectively to the door and a relatively fixed support, a follower casing mounted upon one of said members and projecting laterally therefrom, a follower sliding in said casing, a helical spring abutting said follower, and means for adjusting the tension of said spring, an irregular lateral surface on the other member opposed to said follower, whereby the control of the relative sliding movement of said members and consequently the movement of the door is effected.

13. A door controller comprising relatively sliding members connected respectively to the door and a relatively fixed support, a follower casing mounted upon one of said members and projecting laterally therefrom, a follower sliding in said casing, a helical spring abutting said follower, and means for adjusting the tension of said spring, an irregular lateral surface on the other member opposed to said follower, a signal operated by the movement of said plunger in coöperation with said lateral surface.

14. A door controller comprising telescoping plunger socket members pivotally connected respectively to the door and a relatively fixed support, and means for retarding the extending movement of said members during the latter portion of the closing movement of the door.

15. A door controller comprising telescoping plunger and socket members pivotally connected respectively to the door and a relatively fixed support, a plurality of lateral projections at the inner end of said

- plunger, a follower mounted on said socket member, and means for yieldingly pressing said follower toward said plunger member whereby the extending movement of said members is retarded during the latter portion of the closing movement of the door.
16. A door controller comprising the construction defined in claim 15 together with a laterally projecting stop at the inner end of said plunger which upon engagement with said follower acts to prevent separation of said members.
17. A door controller comprising telescoping plunger and socket members pivotally connected respectively to the door and a relatively fixed support, a signal, and means for actuating said signal from and during the latter portion of the contracting movement of said members.
18. A door controller comprising telescoping plunger and socket members pivotally connected respectively to the door and a relatively fixed support, a signal, and means for simultaneously actuating said signal and retarding the contracting movement of said members during the latter portion of the opening movement of the door.
19. A door controller comprising telescoping plunger and socket members pivotally connected respectively to the door and a relatively fixed support, a plurality of lateral projections on the said plunger member at a predetermined distance from the inner end thereof, a follower mounted on said socket member, and means for yieldingly pressing said follower toward said plunger member, a signal operated by the movement of said follower whereby as the door is opened to a predetermined extent the said projections will move the plunger to operate the signal.
20. A door controller comprising telescoping plunger and socket members pivotally connected respectively to the door and a relatively fixed support, the said plunger presenting a lateral surface inclined toward its axis and toward its inner end, a follower mounted on said socket member, and means for yieldingly pressing said follower toward said plunger member whereby when the inclined surface of the plunger member is opposite the follower the said socket and plunger members will be given an extending movement to close the door.
21. A door controller comprising the construction defined in claim 20 together with a plurality of lateral projections at the inner end of said plunger member to coöperate with the said follower in retarding the extending movement of said members during the latter portion of the closing movement of the door.
22. A door controller comprising the construction defined in claim 20 together with a plurality of lateral projections upon the plunger member at a predetermined distance from the inner end thereof acting to coöperate with the said follower to retard the contracting movement of the said members when the door is opened to a predetermined extent.
23. A door controller comprising the construction defined in claim 20 together with a plurality of lateral projections on said plunger at each end of said inclined surface acting to coöperate with the said follower to retard the latter portions of the relative movements of said members.
24. A door controller comprising the construction defined in claim 20 together with auxiliary means for assisting in the extending movement of said members.
25. A door controller comprising the construction defined in claim 20 together with a helical spring surrounding said members and having its ends held against movement respectively by the socket member and the plunger member when said spring affords auxiliary means for assisting in the extending movement of said members.
26. A door controller comprising the construction defined in claim 25 together with means for adjusting the tension of said spring.
27. A door controller comprising telescoping plunger and socket members pivotally connected respectively to the door and a relatively fixed support, a casing projecting laterally from the socket members, a follower mounted to slide in said casing and contact with the inner end of the plunger member, and a spring in said casing acting to press the follower against the plunger member.
28. A door controller comprising the construction defined in claim 27 together with means for adjusting the tension of said spring.
29. A door controller comprising the construction defined in claim 27 together with a signal mounted on said casing and means for effecting the operation of said signal from the movement of said plunger.

In testimony whereof I have signed my name to this specification.

WILLIAM H. DURANT.
